CLAIM

The ornamental design for a bowl, as shown and described.

DESCRIPTION

FIG. 1 is a top plan view of a bowl.

FIG. 2 is a side elevational view of the bowl of FIG. 1, the opposite side being identical.

FIG. 3 is an end elevational view of the bowl of FIG. 1, the opposite end being identical.

FIG. 4 is a bottom plan view of the bowl of FIG. 1; and, FIG. 5 is a perspective view of the bowl of FIG. 1.
